UNITED STATES PATENT OFFICE.

GEORGE ELMER GRAY, OF DES MOINES, IOWA.

COMBINATION-TOOL.

1,188,931.

Specification of Letters Patent. Patented June 27, 1916.

Application filed February 6, 1914. Serial No. 816,985.

To all whom it may concern:

Be it known that I, GEORGE E. GRAY, citizen of the United States, residing at Des Moines, Iowa, have invented certain new and useful Improvements in Combination-Tools, of which the following is a specification.

My invention relates to combination tools, and it consists in the features and combination and arrangement of parts hereinafter 10 described and particularly pointed out in the claim.

In the accompanying drawings Figure 1 is a side view of a tool embodying my invention; Fig. 2 is a detail view of one of the 15 handle members detached; Fig. 3 is a partial plan view from above along the lines 3—3 in Fig. 1, with the jar wrench removed; Fig. 4 is a partial face view of the head portion with the jar wrench removed; Fig. 5 is 20 a partial section end view along the lines 5—5 in Fig. 1, with the jar wrench removed. Fig. 6 is a detail face view of the sharpener. Fig. 7 is a view of the tack starter.

In these drawings, 1 indicates the main 25 member of the implement having a handle portion 2 and having a guideway at its head portion 1, in which the bar 3 is adapted to slide, said bar at its upper end 4 providing a nail hammer and at its lower end 5 providing a tack hammer. This sliding bar is 30 operated by a handle member 6, which is pivotally mounted by a pin 7, to the head 1 of the main member, bifurcations of the end of the member 6 being rounded at 8 and 35 engaging cutaway portions 9 on the sides of the slidable bar 3 so that by pressing the handles 2 and 6 together, the sliding bar 3 may be projected downwardly to make the end 5 protrude beyond the head portion 1. 40 The members are held apart by a spring 10 attached at one end to a bent hook 11 formed by the bottom of the handle 6 between the bifurcations 8 of its end, and at the other end to a lug 12, struck out of the metal of 45 the handle portion 2 and bent inwardly also to form a hook. Sliding bar 3 has a notch 13 formed in its front face and by projecting the bar this notch may be exposed to receive a piece of glass for breaking the same, or the 50 notch may be used to receive the edge of a pan, and after the edge is in the notch, by releasing the pressure on the handles the spring 10, acting through the member 6, will cause the bifurcations 8 thereof to tend to draw 55 the bar 3 inwardly, and thus firmly grip the edge of the pan, and then the implement

may be used as a handle for carrying the pan from place to place, the pan being gripped between the lower side of the notch and the adjacent portion of the head 1. At 60 the opposite end of the sliding bar from where the notch 13 is located I provide a punch bar 14 integral with a projection of the bar 3 and a corresponding opening 15 therefor in the handle 2 wherein tickets, 65 paper, leather or other articles may be punched.

At or near the lower portion of the front face of the head 1 I mount a nail and tack lifter 16 provided with openings to receive 70 lugs 17 and 18 carried by the head portion 1 for securing this lifter to the main head of the implement. The lug 18 is in the form of a headed stud and the opening in the tack lifter is in the form of a key hole slot and fitting thereover, and the lug 17 is plain, that is, without any head as is also the opening fitting thereover. This nail and tack lifter may be removed and replaced by any similar implement, such as a staple lifter, for 75 which purpose it is only necessary to exert pressure upon the lower part of the lifter to pry it off from the lug 17, and then an upward sliding and a tilting pressure to free it from the lug 18. The arrangement is such 80 that a direct upward lift may be exerted upon a tack or nail, thus withdrawing the same without bending and the strain exerted on the lifter is such as to tend to hold the same 85 in interlocking relation with lug 18. 90

A fruit jar wrench is shown at 19, consisting of a loop or partial ring of wire having a hooked end 20 adapted to engage the opening in the lug 18 of the head of the implement, the other end of the wire wrench being bent to enter an opening at 21 in the slidable bar 3. In order to use this wrench, the wire loop is placed around the cap of the jar and will firmly engage the same by 95 pressing the handles 2 and 6 together, which 100 action results in sliding the bar 3 downwardly and causing the two ends of the wire wrench to approach each other. This wire wrench by its resilient action also aids the spring 10 to return the bar 3 and the handle 105 members to their normal position shown in Fig. 1. The wire wrench may be readily removed by exerting pressure upon its ends in a manner which will be obvious from the drawing. This wire wrench must be removed 110 before the tack lifter can be removed, as the end 20 engages the lug 18

which secures the tack lifter to the head portion 1.

I show at 22 a pipe wrench formed of serrated curved portions of the handles 2 and 6 adjacent the pivot thereof, and also at 23 a wire cutter formed by straight edges on the opposing members 2 and 6, which have a shearing action in relation to each other when these members are pressed together.

10 The opening in the handle 2, at 24, provides a winding device for the spring of a window shade roller, it being suitably disposed to engage the projecting end on said roller. This also may serve as a Presto-lite key.

An arm 26 is pivoted to the handle member 2 by means of a pin 25 passing through both edges of the handle member carrying a glass cutter 27. The end of this handle member has three notches at 29 to provide a knife and scissors sharpened as shown. The other handle member 6 is provided with a scale or inch rule extending along its straight edge 30. This arm 6 terminates in a flattened portion 31 forming a screwdriver. The arm 6 is provided also with a stop projection 32, which bearing upon the inner side of the arm 2 will limit the position of these arms in relation to each other. 30 By removing the pin 7 the implement may be taken apart as the arm 6 can then be removed from the arm 2, and its forks 8 removed from engagement with the slidible

bar 3, and this will permit the removal of this bar so that the implement may be dismembered. The handle members 2 and 6 are of channel form in cross section, and the tracing wheel lies in the channel of the member 2 when folded into position of non-use.

40 At 33 is an opening to serve as a tin strip can opener.

34 is a cork screw secured to the handle 6, and 35 is a tack or nail starter, that is, an opening in which the head of the nail or 45 tack can be placed to hold it securely until it can be started into the wood.

I claim as my invention:—

In an implement, a head, a handle connected to said head; a bar slidably mounted 50 in said head transversely to said handle; a tack claw secured to said head adjacent said bar; means normally retracting said bar in said head; and a second handle pivotally connected with said head and operatively connected with said bar, said handle being bifurcated, and there being notches in the sides of said bar operatively engaged by the bifurcations of said handle, substantially as described.

60 In testimony whereof, I affix my signature in presence of two witnesses.

GEORGE ELMER GRAY.

Witnesses:

MAUD A. CHAPIN,
MRS. O. O. LITTELL.
